ATTORNEY

UNITED STATES PATENT OFFICE.

ALBERT G. HIGGINS, OF KANSAS CITY, MISSOURI.

SHIELD ATTACHMENT FOR PICKS.

1,358,206.

Specification of Letters Patent. Patented Nov. 9, 1920.

Application filed January 27, 1919. Serial No. 273,244.

To all whom it may concern:

Be it known that I, ALBERT G. HIGGINS, a citizen of the United States, residing at Kansas City, in the county of Jackson, State of Missouri, have invented a certain new and useful Improvement in Shield Attachments for Picks, of which the following is a full and exact specification.

The present invention relates to digging implements, such as picks, mattocks, and the like, and the primary object in view is to provide a shield member for attachment to such implements for the purpose of protecting the workman using the tool from the flying particles which are usually thrown out from the working point of the tool, especially when digging into hard materials like asphalt, cement, ice, and so forth.

It is also sought to devise a shield attachment of this character which will permit suitable adjustment of the same to suit the individual requirements of the workman using the tool.

A further object in view is to provide an improved device adapted to fulfil the desired protecting function while at the same time interfering in no way with the proper use of the tool.

With these general objects in view the invention will now be described with reference to the accompanying drawing illustrating one form of construction which has been devised for embodying the improvement, after which the novel features thereof will be set forth and defined in the appended claims.

In the drawing—

Figure 1 is a perspective view showing the present improved shield attachment in its operative relation to the tool and illustrating the mode of using the same;

Fig. 2 is a side view on an enlarged scale, showing a pick with a portion of its handle broken away and with the shield attachment applied thereto;

Fig. 3 is a sectional view taken on the line 3—3 of Fig. 2, but on a larger scale; and

Fig. 4 is a detail section taken on the line 4—4 of Fig. 3, and on a still larger scale.

Referring to the said drawing in detail, this shows a pick 5 having the handle portion 6, to which is applied the present improved shield element 7 comprising a plate 55 of suitable size and shape, suspended by means of a wire attaching structure from

said handle 6. This wire is twisted and shaped to form eyes or loops 8 for fitting slidably and frictionally over the handle 6 and connected by the spring bowed portion 10, whereby said eyes or loops 8 are held in any given set position on the handle. The end portions 11 of the wire project downwardly in forked relation through attaching loops or keepers 12 formed on one 65 face of the shield plate 7, as shown more clearly in Figs. 3 and 4, the said end portions 11 being formed with a series of notches 13 for selective engagement with said keepers 12, with which the notches 13 70 are held in retaining engagement by the outward spring action of the end portions 11 of the wire. By means of this construction the shield member is supported by the lower projecting ends of the wire in suspended 75 relation to the rear of the working point of the pick, and may also be adjusted upward or downward in said ends 11 to the desired elevation.

The operative character of the device is 80 readily apparent by reference to the illustration of its use as shown in Fig. 1. The shield attachment, with the shield plate 7 properly proportioned, affords a means whereby a protected zone, bounded by the 85 diverging lines A and B, including the upper portion of the workman's body, is formed, within which zone the flying particles from the working point of the pick are excluded. The arrangement of the attaching wire is also such that the position 90 of the shield plate may be set into practically any position best suited to the needs of the workman. For example, the device may be shifted to any position along the handle 6 by 95 simply compressing the spring bowed portion 10 slightly (which may be done by pressure at the loops 8 either above or below the handle), and this results in releasing the grip of the loops 8 on the handle and permitting them to be slid either toward or from the pick 5, after which, by releasing the pressure on the spring bow 10 the said loops 8 are allowed to firmly reengage the handle. 100 The elevation of the shield plate 7 may be 105 adjusted by means of the notches 13 and keepers 12, the notched ends of the wire being pressed together and shifted in either direction through said keepers, this mode of adjustment being an advantage in regulating the position of the shield plate as the pick becomes worn. The oval cross-section 110

of the handle prevents any rotation of the attachment on the handle, but the flexible nature of the wire will permit that portion below the loops 8 to be bent either backward or forward or laterally in either direction so that the exact required position of the shield element may be obtained.

It will thus be seen that a simple, compact and inexpensive device is provided for fulfilling the required objects of the invention, as the space within the described shielded zone is maintained practically free from any of the objectionable flying particles of material, and the workman is obviously enabled to operate with far greater comfort and safety. Moreover, the attachment does not affect or interfere in any way with the operation of the tool, nor does it obstruct the workman's view of the working point thereof when the tool is elevated. Again, if he should desire to operate for any reason without the use of the protecting device, the pick may simply be reversed, using the other point thereof; or, obviously, if preferred, the protecting device may itself be reversed on the tool by simply sliding it off the handle and projecting the shield portion in the opposite direction.

While I have illustrated and described

what I now regard as the preferred form of construction for embodying the invention, I desire to reserve the right to make all such formal changes or modifications as may fairly fall within the scope of the appended claims.

Having described the invention, what I claim as new and desire to secure by Letters Patent, is:

1. The combination with a pick having a handle, of a shield provided with a pair of spaced loops adapted to fit slidably over said handle, said loops being provided with a resilient connecting member adapted to yieldingly spread said loops into frictional engagement with said handle.

2. The combination with a pick having a handle, of a shield provided with a series of keepers, and means for attaching said shield to said pick handle, said attaching means including a pair of downwardly extending spring arms provided with a series of notches adapted for adjustable engagement with said keepers and maintained in engagement therewith by the spring action of said arms.

In witness whereof I hereto affix my signature.

ALBERT G. HIGGINS.
